ATTORNEY

UNITED STATES PATENT OFFICE.

JAMES M. HADDEN, OF POUGHKEEPSIE, NEW YORK.

GAS APPARATUS.

SPECIFICATION forming part of Letters Patent No. 628,000, dated July 4, 1899.

Application filed September 30, 1898. Serial No. 692,819. (No model.)

To all whom it may concern:

Be it known that I, JAMES M. HADDEN, a citizen of the United States, residing at Poughkeepsie, in the county of Dutchess and State 5 of New York, have invented new and useful Improvements in Gas Apparatus, of which the following is a specification.

My invention relates to improvements in illuminating-gas apparatus, and more particularly to the superheater of the Lowe or other standard type of gas apparatus; and the object is to improve the construction and increase the efficiency of the apparatus by collecting the waste gases and other heated products of combustion, which heretofore have been allowed to escape from the superheater into the atmosphere, and conducting them to the fuel-economizer, which will utilize the heat for steam-making purposes.

With this object in view the invention consists in the construction, combination, and arrangement of the apparatus, as will be hereinafter more fully described, and particularly pointed out in the claims.

The figure in the drawing is a diagrammatic view of the upper end of a gas-superheater and the connections embodying my invention.

1 denotes the superheater, provided at its upper end with a central opening 2, which is closed by a valve 3, carried by the parallel arms 4 4, fixed on the shaft 5, journaled in the brackets 6 6, secured to the upper end of the superheater. One end of the shaft 5 terminates in a crank-arm 7, from which a connecting-rod 8 extends to a hand-lever 9, fulcrumed to the external face of the wall of the superheater. The opposite end of the shaft 5 also terminates in a crank-arm 10, from which a rod 12 extends to the projecting arm 40 of the damper 13, fulcrumed in the casing 14, forming a part of the horizontal flue 15, leading from the hood 16, supported by the standards 17 17 above the superheater. The upper end of the hood communicates with the stack 18.

19 represents an annular horizontal shoulder or collar fixed in the hood to form a seat for the damper 20, fixed on the rock-shaft 21, and one end of this shaft terminates in a vertical arm 22, provided with a pendulating weight, as shown.

From the arm 22 a chain or rope 23 extends

over suitable pulleys, and thence downward, as shown, where its free end terminates in a grip-ring 24, and when the damper 20 is in 55 the position shown with arm represented in full lines it cuts off the communication between the hood and the stack and leaves the inner end of the flue 15 open.

By pulling down on the grip-ring 24 the 60 damper-arm 22 is brought to a vertical position, and the momentum imparted to the weight carries the arm beyond the center and over to the position shown in the dotted lines, with the damper resting against and closing 65 the end of the flue 15, so that communication with the flue is cut off and at the same time communication is established between the hood and the stack.

Heretofore the large volume of heated gases 70 which escaped from the superheater when the valve 3 was opened was lost by passing through the hood and stack into the atmosphere, whereas in the present instance the damper 20 being closed when the valve 3 is raised the damper 13 is opened, which permits the gases arising from the superheater to pass from the hood through the flue 15, whence they are conducted to the fuel-economizer, (not shown,) so as to utilize the heat for steam-making purposes.

Although I have specifically described the construction and relative arrangement of the several elements of my invention, I do not desire to be confined to the same, as such changes 85 or modifications may be made as clearly fall within the scope of my invention without departing from the spirit thereof.

Having thus fully described my invention, what I claim as new and useful, and desire to 90 secure by Letters Patent of the United States, is—

1. In combination, the superheater, the hood, the stack and an independent flue communicating with said hood, a damper located 95 in the hood and adapted to alternately cut off communication between the hood and stack or flue, an independent damper located in the flue, a valve on the superheater, and means for simultaneously operating said valve and 100 flue-damper, as and for the purpose set forth.

2. The combination with the superheater and its valve, of the hood, its stack and the horizontal flue, of a damper located in said

flue and operatively connected to said valve, as and for the purpose set forth.

3. In a gas-making apparatus, the superheater 1, the valve 3 and shaft 5 provided with the crank-arm 10, the hood 16, the damper 20 mounted in said hood, the stack 18 and horizontal flue 15, communicating with said hood, the damper 13 mounted in said flue and the rod 12 connecting said damper 13 and crank-arm 10, substantially as shown and described.

4. In a gas-making apparatus, the combination with the superheater, of a valve communicating with said superheater, a hood 15 mounted above said valve and provided with

a stack, a fuel-economizer flue communicating with said hood, a damper mounted in the hood and adapted to cut off communication between the hood and stack or flue, and a damper located in said flue and operatively connected with the superheater-valve, substantially as and for the purpose set forth. ²⁰

In testimony whereof I have hereunto set my hand in the presence of two subscribing witnesses.

JAMES M. HADDEN.
